UNITED STATES PATENT OFFICE.

LERoy EDGAR RUSSELL, OF DEPOSIT, NEW YORK.

HEATING-FURNACE.

1,215,199.

Specification of Letters Patent.

Patented Feb. 6, 1917.

Application filed March 18, 1915. Serial No. 15,259.

To all whom it may concern:

Be it known that I, LEROY E. RUSSELL, a citizen of the United States, and a resident of Deposit, in the county of Broome and State of New York, have invented a new and Improved Heating-Furnace, of which the following is a full, clear, and exact description.

This invention relates to heating furnaces of the hot air type, and the general objects of the invention are to improve the construction of the internal structure so as to be more efficient, comparatively simple and inexpensive to manufacture, and of durable and substantial design.

A more specific object of the invention is the provision of a fire-box, combustion chamber and ash-box of novel design, whereby a large radiating surface is provided for enabling a higher abstraction of heat from the fuel, there being a novel arrangement of smoke flues in connection with the combustion chamber, whereby the air passing through the furnace is effectively heated.

With such objects in view, and others which will appear as the description proceeds, the invention comprises various novel features of construction and arrangement of parts which will be set forth with particularity in the following description and claim appended hereto.

In the accompanying drawing, which illustrates one embodiment of the invention and wherein similar characters of reference indicate corresponding parts in all the views,

Figure 1 is a central vertical section of the furnace;

Fig. 2 is a horizontal section on the line 2—2, Fig. 1, through the ash-box, drawn on a reduced scale;

Fig. 3 is a horizontal section on the line 3—3, Fig. 1, through the combustion chamber portion of the furnace; and

Fig. 4 is a horizontal section on the line 4—4, Fig. 1, through the fire-box.

Referring to the drawing, A designates the casing of the furnace, which has a fresh air inlet 1 at the bottom of its rear portion, and at the top it is provided with numerous hot air distributing ducts 2 arranged in any suitable manner. The internal structure comprises an ash-box 3, a fire-box 4, a combustion chamber 5 and a surrounding annular smoke flue.

55 The ash-box 3 is a metal casting or other

structure supported on legs or equivalent means 7, and in horizontal dimensions it is considerably smaller than the casing, so that ample space is provided for permitting the incoming air to circulate around the ash-box at all points.

The front of the ash-box is provided with an opening 8 at the front wall of the casing A, and this opening is provided with a door 9. The rear portion of the ash-box is provided with external vertically disposed ribs 10 for increasing the heat-conducting and radiating surface. At the top of the ash-box is a grate 11 of suitable construction for holding the fuel.

The fire-box 4 is a cylindrical casting and has on its outside a plurality of vertical ribs 12 for increasing the heat-conducting and radiating surface, and this fire-box is in diameter considerably smaller than the casing A, for allowing air to circulate freely at all points along the ribs 12. The fire-box rests on and is fastened to the ash-box and it in turn supports the combustion chamber 5. This combustion chamber is formed by an approximately cylindrical-shaped body 13 having a dome 14 and it has on its vertical wall internal and external vertical ribs 15 and 16 for increasing the transmission of heat from the fire gases to the air to be heated. The dome 14 also has internal and external ribs 15' and 16'. The combustion chamber is of approximately the same diameter as the fire-box, and therefore the air to be heated flows freely upwardly along the outside of the combustion chamber, the dome of which is somewhat below the top of the casing A to provide a distributing space for the hot air. Disposed in the same horizontal plane with the combustion chamber and concentrically arranged with respect thereto are two oppositely disposed approximately semi-circular portions 17 and 17' of the smoke flue which communicate with the combustion chamber through an opening 18 at the front of such combustion chamber. The casing is enlarged at its upper portion to accommodate the smoke flue, and at the bottom of the enlargement is an annular shoulder over which the smoke flue lies. The inner circular wall of the smoke flue is of substantially the same diameter as the bottom portion of the casing, so that a straight unbroken upflow of the air through the casing is pro-

100

vided. The flues are formed by concentric walls 19 and 20, the front ends of the wall 19 being united with the cylindrical wall of the combustion chamber by the bends 21 which form opposite walls of the opening 18, which latter serves as an outlet for the fire gases, and also as a feed opening for the coal. Therefore the opening 18 is in line with an opening 22 in the front portion 10 of the wall 20, and provided for this opening 22 is a door 23 through which the furnace is coaled. The annular horizontal plate 24 in line with the bottom of the combustion chamber connects the three concentric walls 13, 19 and 20 and cuts off communication between the hot air space of the chamber and the combustion system. The portion of the horizontal plate 24 between the walls 13 and 19 has openings 25, so that 20 the air can pass upwardly between the combustion chamber 5 and the smoke flue, the tops of the flues being closed by a horizontal web 26. The structure between the combustion chamber and flue is stiffened by 25 radial connecting webs 27, as shown in Figs. 1 and 2, these webs being vertical so as not to interfere with the free upward flow of the air that is being heated. Since the air flows between the flue and the combustion 30 chamber, the air is effectively heated, and by the time the fire gases reach the outlet 28, where the flue sections 17 and 17' join, a large amount of the heat is abstracted. The ribs of the combustion chamber assist 35 materially in transmitting the heat of combustion to the air.

From the foregoing description taken in connection with the accompanying drawing the advantages of the construction and 40 method of operation will be readily understood by those skilled in the art to which the invention appertains, and while I have described the principle of operation, together with the structure which I now consider to be the best embodiment thereof, I 45 desire to have it understood that the structure shown is merely illustrative and that

Copies of this patent may be obtained for five cents each, by addressing the "Commissioner of Patents, Washington, D. C."

such changes may be made when desired as are within the scope of the appended claim.

Having thus described my invention, I 50 claim as new and desire to secure by Letters Patent:

A furnace comprising a casing circumferentially enlarged at its upper portion and having a cold air inlet at its bottom 55 and hot air outlets at the top, there being an annular shoulder between the bottom of the enlarged portion and the lower portion of the casing, and a structure within the casing for burning fuel, said structure comprising an ash-box, a fire-box mounted thereon and having a smooth interior and vertical integral ribs on its outer surface, there being a substantial space between the wall of the casing and the ribs on the fire- 60 box, a combustion chamber supported on the top of the fire-box and having internal and external ribs on its circumference and extending vertically, and internal and external ribs on the top, a flue connected with 65 the front of the combustion chamber and extending in opposite directions around the same and uniting at the rear, and an outlet connected with the rear of the flue, said flue being spaced from the wall of the combustion 70 chamber and the intermediate space communicating with the space between the casing, and the fire-box for permitting an unobstructed up-flow of air from the bottom of the casing to the space between the 75 top thereof and the top of the combustion chamber, said flue being disposed in the enlarged part of the casing and directly over the said shoulder, there being an opening at the juncture of the flue with the combustion 80 chamber through which coal is supplied to the fire-box.

In testimony whereof I have signed my name to this specification in the presence of two subscribing witnesses.

LEROY EDGAR RUSSELL.
